SWITCH CONTROL DEVICE

Erich Dobler and Ludwig Holm, Stuttgart, Germany, assignors to Robert Bosch Aktiengesellschaft, Stuttgart, Germany

Application July 5, 1935, Serial No. 30,004
In Germany July 27, 1934

8 Claims. (Cl. 200—140)

The present invention relates to a controlling device, which is adapted more especially for the controlling of refrigerating plants.

It is known in controlling devices to use a snap-spring having two stable end-positions for the sudden effecting of switch movements. This snap-spring is struck by the member dependent on whose position the switching operation is to be carried out, and flies over from its one end-position into the other end-position, and thereby switches any circuit on or off. It has been suggested to provide an elastic connecting piece arranged between the snap-spring and the controlling member dependent on whose position a switching operation is to be effected. By this means a control operation does not take place at each of the smallest movements of the controlling member.

In the controlling devices of this kind hitherto known the controlling member consists of a rocking lever, to the side of which facing the bottom of the switch casing the elastic connecting piece in the form of leaf-springs is fastened with side faces directed at right angles to the casing bottom. In this construction, these two controlling members take up a comparatively large amount of room. As they lie above each other, and also above the snap-spring operated by them, they involve a relatively high switch casing. Further, the controlling lever must have a broad surface parallel to the switch bottom, so that it may afford sufficient room for fastening the holding bolt of the leaf-spring.

The construction is substantially simplified and made more compact according to the invention wherein the controlling lever takes the form of a metal strip which is narrow in the rocking direction, to the side faces of which are fastened the leaf-springs which bear with their broad faces on the snap spring.

An example of construction according to the invention is shown in the drawing, in which:—

Figure 1 is a plan view, with the upper switch cover removed.

Figure 2 is a section on the line 2—2 of Fig. 1.

Figure 3 a section on the line 3—3 of Figure 1, and

Figure 4 is a detailed view, looking to the right of Figure 1, of the switch resetting mechanism.

10 is a thermostat, which responds to the temperature of the refrigerating chamber of a refrigerating plant. It consists of a bellows 11, which is filled with a liquid the volume of which varies greatly on a change of temperature, and 55 is loaded by a spring 12, the compression of which

can be varied by a screw 38 when an operating knob 13 is turned. The interior of the bellows 11 is connected by a pipe 14 with a temperature-sensitive element (not shown), arranged in the chamber whose temperature is to be controlled. 5 The resiliently loaded bellows 11 and the spring 12, together with the operating knob 13, are mounted on a plate 15, which is inserted in the lower part 16 of a switch casing and is connected thereto by screws.

The movements of the bellows 11 produced by alterations in temperature are transmitted by means of a spindle 18 to a lever 20, of metallic strip form, and pivoted on a pin 19, two leaf-springs 21 being laterally riveted to said lever. 15 The leaf-springs 21 engage a snap spring 22, the ends of which are mounted in bearing pins 23, which are also fastened on the plate 15. The snap-spring 22 carries a contact 24, the counter-contact 25 of which is resiliently seated on a 20 carrier member 26 secured to the plate 15. The lever 20 is not rigidly connected to the spindle 18 of the thermostat 10, on the contrary it bears loosely against a pin 27 carried through the spindle 18, and is pressed against said pin by the bent 25 up straight end of a helical spring 28. Such a resilient coupling has the advantage that no great frictional forces occur on the movement of the thermostat bellows. The helical spring 28 is fitted on a bolt 29, which, like the other part 30 of the switch, is secured to the plate 15. To the switch plate 15 is also connected a support 30 for a bimetallic strip 31 which serves as an excess current safety device. One free end of a lever 33 engages in a hole 32 in the bimetallic 35 strip, and the other end of the lever bears on the lever 20 which operates the snap-spring 22 of the switch. 34 is a wire coil which heats the bimetallic strip when an excess current occurs. 35 is a starting switch, which, together with the 40 remaining parts of the switch, can be arranged in the casing 16.

The manner of operation is as follows:—

When the parts are in the position shown in Figure 1 the contacts are closed. If now the 45 temperature in the refrigerating chamber sinks, then the volume of the liquid therein becomes smaller and the spring 12 compresses the bellows 11. Consequently, the spindle 18 is moved to the left whereby the lever 20 is rocked to the left, 50 so that one of the leaf-springs 21 presses against the snap-spring 22, which now flies over from one end-position into the other end-position, and thereby separates the contacts 24, 25. If the current is to be switched off, the switch knob is 55

correspondingly turned, by which one end of the lever 33 snaps out of the opening 32, and the other end of the lever 33 is pressed by means of a spring 36 against the lever 20, which brings the snap-spring 22 into the other position for flying over, whereby the contacts 24, 25 are released. When an excess current occurs, the resistance wire 34 heats the bimetallic strip 31, which bends owing to heating, whereupon one end of the lever 33 springs out of the hole 32 and the other end is pressed by means of the force of the spring 36 against the lever 20, which causes the snap spring 22 to fly over so that the current is switched off. The switch can be reset by turning knob 13 counterclockwise, at which time the beveled end of a lever 40 pivotally mounted on disk 39 will engage the lever 33 and move it upward to reset the switch. A spring 41 normally holds lever 40 against a pin 42, the spring yielding to permit said lever to swing on its pivot without actuating lever 33 when the knob 13 and disk 39 are turned clockwise.

The leaf-springs 21 are preferably regularly tapered from the place where they are riveted towards the free end which is in engagement with the snap-spring, so that on the displacement of a rider 37 the curve of the leaf-springs is altered so as to regularly rise or fall. By this means the switch device can be adjusted so as to be very sensitive when fixing up the apparatus.

It is further preferable to make the adjustable rider 37 in U-shape with an eye-shaped web. By this means the rider can be easily gripped to move it, yet nevertheless in any position presses the leaf-springs 21 resiliently on the flat faces of the lever 20. In connection with the lateral arrangement of the leaf-springs 21, this form of rider has also the advantage that the rider is held by its own springiness alone on the leaf-springs 21 and the lever 20.

We declare that what we claim is:

1. A switch control device for apparatus such as refrigerators, comprising a thermostat, a rocking lever of metallic strip form angularly displaceable by said thermostat according to temperature variations, and with the faces of said lever extending laterally of its direction of movement, a pair of leaf springs, the flat faces of which are secured to the flat faces of one end of said rocking lever, a snap spring having a flat face extending between and having a direct flat face to face contact with said leaf springs and which is stable in two end positions of displacement, and switch contacts, one of which is carried by said snap spring.

2. A switch control device for apparatus such as refrigerators, comprising a thermostat, a rocking lever of metallic strip form angularly displaceable by said thermostat according to temperature variations with the faces of said lever extending laterally of its direction of movement, a pair of tapered leaf springs the flat faces of which are secured to the flat faces of one end of said rocking lever, and the cross-section of each of which is gradually reduced towards the free end thereof, a snap spring having a flat face extending between and having a direct flat face to face contact with said leaf springs, and which is stable in two end positions of displacement, and switch contacts, one of which is carried by said snap spring.

3. A switch control device for apparatus such as refrigerators, comprising a thermostat, a rocking lever of metallic strip form, angularly displaceable by said thermostat upon a temperature

variation with the faces of said lever extending laterally of its direction of movement, a pair of tapered leaf springs the flat faces of which are secured to the flat faces of one end of said rocking lever, a displaceable rider resiliently embracing said leaf springs and said lever intermediate their ends, a snap spring having a flat face extending between and having a direct flat face to face contact with said leaf springs and which is stable in two end positions of displacement, and switch contacts one of which is carried by said snap spring.

4. A switch control device for apparatus such as refrigerators, comprising a thermostat, a rocking lever of metallic strip form, angularly displaceable by said thermostat upon a temperature variation, a pair of tapered leaf springs the flat faces of which are secured to the flat faces of one end of said rocking lever, a displaceable rider consisting of a U-shaped yoke and an eye-shaped web, resiliently embracing said leaf springs and said lever intermediate their ends, a snap spring having a flat face to face contact with said leaf springs and which is stable in two end positions of displacement, and switch contacts one of which is carried by said snap spring.

5. A switch control device for apparatus such as refrigerators, comprising a thermostat, an element adapted to be operated by said thermostat according to temperature variations, resilient means one end of which is secured to said element, a snap spring adapted to be snapped over from one position to another and vice versa by the other end of said resilient means, and means for regulating the strength of said resilient means, the cross-section of said resilient means gradually decreasing from its secured end to the other end, such regulating means being movable on said resilient means to regulate the effective length and cross-section thereof.

6. A switch control device for apparatus such as refrigerators, comprising a thermostat, a lever angularly displaceable by said thermostat according to temperature variations, resilient means one end of which is secured to said lever, a snap spring actuated by the other end of said resilient means and arranged to snap from one position to the other and vice versa for quickly making or breaking an electric circuit, and a displaceable rider embracing said resilient means and varying, when displaced, the resilient strength of said resilient means, the cross-section of said resilient means gradually decreasing from its secured end to the other end, such regulating means being movable on said resilient means to regulate the effective length and cross-section thereof.

7. A switch control device for apparatus such as refrigerators, comprising a thermostat, a lever angularly displaceable by said thermostat according to temperature variations, two leaf springs at opposite faces of said lever, one end of each leaf spring being secured to said lever, a snap spring in adjacent connection with and actuated by the other ends of said leaf springs and arranged to be snapped from one position to the other and vice versa for quickly closing or breaking an electric contact, a displaceable rider embracing said leaf springs to adjust the resilient strength of the leaf springs, the cross-section of said leaf springs diminishing from their secured ends to their other ends to reduce the stiffness of said leaf springs toward said other ends, displace-
ment of said rider relative to said leaf springs varying the effective length and cross-section thereof.

8. A switch control device for apparatus such as refrigerators, comprising a thermostat, an element adapted to be operated by said thermostat according to temperature variations, a snap spring adapted to be snapped over from one position to another and vice versa, resilient means for transferring the movement of said element to said snap spring, the two ends of said resilient means being connected with said element and said snap spring, the one end being connected solidly and

the other loosely, the cross-section of the resilient means gradually decreasing from its secured end to the other end, and means for regulating the strength of said resilient means, such regulating means being movable on said resilient means to regulate the effective length and cross-section thereof. 5
